UNITED STATES PATENT OFFICE.

JUDSON B. FREIDAH, OF NEW YORK, N. Y.

TRAFFIC SIGNAL.

Application filed October 24, 1925. Serial No. 64,688.

This invention relates to accessories for motor vehicles designed as a means for signaling to approaching or following traffic that a turn or stop is contemplated by the operator 5 of the vehicle to which it is applied, the same being in the nature of an improvement over my copending application, Serial No. 678,278, filed December 3, 1923. My prior 10 application was particularly designed to be completely operated electrically, whereas in the present application the device includes a combination of electrically and mechanically operated means for visualizing the signals.

15 One of the principal objects of the present invention is to provide a traffic signaling device for motor vehicles, which is comparatively simple in its construction and mode of operation, inexpensive to manufacture and 20 install, highly efficient, and thoroughly reliable and positive in its action.

With the above recited and other objects in view, reference is had to the following specification and accompanying drawings in which 25 there is exhibited one example or embodiment of the invention which is in no way intended as a limitation upon the scope of the appended claim as it is to be clearly understood that variations and modifications which 30 properly fall within the scope of said claim may be resorted to when found expedient.

In the drawings—

Figure 1 is a perspective view illustrating the signal in its applied position on a motor 35 vehicle;

Fig. 2 is an enlarged rear view thereof;

Fig. 3 is a plan view of the same;

Fig. 4 is a sectional view taken approximately on the line 4—4 of Fig. 5;

Fig. 5 is a sectional view taken approximately on the line 5—5 of Fig. 4;

Fig. 6 is a sectional view through the manipulating knob and the manual lamp-controlling switch;

Fig. 7 is a face view of the front signaling member or plate;

Fig. 8 is a diagrammatic view of the electric switch.

Referring to the drawings by characters of reference, 10 designates a casing preferably of circular form having a front section 11

constituting a cover which is hinged at 12 to the body of the casing and the body is provided with a laterally and inwardly projecting tubular arm 13 which is suitably supported by a clamping device 14 from the windshield W of an open car or in other suitable manner from the body of a closed car. The rear wall 15 of the casing 10 and the front wall of the cover or front section 11, are provided with aligned window openings 18 and 19 each covered by a transparent panel 20. Preferably the outer surface of the lower portion of the rear wall 14 has mounted thereon a rear view mirror 21 whereby the device serves both as a signaling device and a means for observing following traffic.

A bearing strap 22 has its major portion arranged horizontally within the casing with one extremity 23 bent upwardly at an angle, the opposite terminals of said strap being secured to the annular wall of the casing body. The medial portion of the strap is formed with a bearing 24 in which a shaft 25 is journaled, the said shaft being disposed axially of the casing. The bearing strap 22 and bearing 24 are vertically slotted centrally to accommodate a pinion 26 keyed to the shaft 25. At its front and rear ends the shaft 25 has secured thereto for turning movement therewith, front and rear disks of opaque material. The disk 27 is provided with circumferentially spaced cutout portions 29 and 30 of a configuration to represent hands pointing in opposite directions, while the rear disk 28 is provided with circumferentially spaced cutout portions 31, 32 and 33, the cutout portion 31 being of a configuration simulating an upraised hand, and the latter cutout portions 32 and 33 representing hands pointing respectively in opposite directions, which latter cutout portions 32 and 33 are disposed in alignment with the cutout portions 29 and 30.

The inner end of the tubular arm in addition to carrying the clamping means 14, supports and communicates with a housing 34 which is disposed within the confines of the upper part of the vehicle and within convenient reach of the operator. Extending through the rear wall of the housing 34, is a

tubular shaft 35, which has attached to the portion arranged within the housing, a pinion 36, the teeth of which mesh with the teeth of a rack bar 37 which extends through the tubular arm 13 and into the casing 10. The outer end of the rack bar 37 has telescopically associated therewith a rack bar 38, which is secured to the rack bar 37 by a retaining screw 39. The teeth of the rack bar 38 mesh with the teeth of the pinion 26 so that turning movement imparted to the tubular shaft 35 will impart a similar turning movement to the shaft 25 for turning the disks 27 and 28 in order to selectively dispose the alined cutout portions 29 and 32 or 30 and 33 in registry with the window openings 18 and 19 of the casing, or the cutout portion 31 in registry therewith.

The cutout portions 29, 30, 31, 32 and 33 are filled with a translucent material 40 which is of a color or shade not readily distinguishable from the color or shade of the disk when an external light is cast thereon but which upon the casting of light reflections thereupon through renders said filled cutout portions clearly distinguishable from the disks to display the same.

Supported from the bearing strap 22 and approximately in alinement with the window openings 18 and 19, is an electric lamp, 41, mounted in a lamp socket 42 from which a circuit return wire 43 leads to one pole of a battery or other source of supply 44. From the opposite pole of the battery or source of supply 44, a circuit wire 45 leads to and is connected with branch feed wires 46 and 47, the former being connected to one of a pair of spaced contacts 48 of a switch including a bridging element 49, the remaining spaced contact 48 being connected by a circuit wire 50 to a stationary contact 51, which stationary contact 51 is in turn connected by a branch feed wire 52 to the feed conductor 53 leading to the lamp socket. The conductor 53 is connected by a branch circuit wire 54 to a second stationary contact element 55. The contact elements 51 and 55 are spaced from each other and mounted upon a suitable arcuate insulated support 56 within the housing 34. The tubular shaft 35 has secured thereto a radial arm 57, the free end of which has connected thereto and insulated from therefrom, a contact element 58 connected to the branch circuit wire 47 and movable with the arm 57 when the tubular shaft is turned. The spacing of the contacts 51 and 55 is such that when the shaft 35 is rotated to dispose the alined cutout portions 29 and 32 and 30 and 33 in registry with the window openings 18 and 19, the movable contact element 58 will respectively engage with the contacts 55 and 51 so that the lamp 41 will be energized and lighted to display through the front and rear window openings 18 and 19, the pointed hands, thereby indicating to following or

approaching traffic that a turn is contemplated.

However, when the vehicle is traveling in a straight direction, the shaft 35 will be turned to an intermediate position disposing the pointed hands out of registry with the window openings and the contact element 58 consequently out of contact with either of the contact elements 51 or 55, to de-energize and extinguish the lamp. In this relation the upraised open hand designated by the cutout portion 31 will be disposed in alinement with and displayable through the rear window opening 18. In order to visualize through the window opening, said cutout portion 31, the lamp 41 is energized or lighted by bringing the bridging element 49 into bridging relation with the spaced contacts 48. The switch which includes the spaced contact elements 48 and bridging element 49, is enclosed in a hollow knob 60, which is secured to the rearwardly projecting end of the hollow shaft 35 by a set screw 61. The circuit wires 46 and 50 are led through the tubular shaft 35 and connected to the spaced contact elements 48 which are supported by an insulated member 62 in which the bridging element 49 is arranged. The bridging element is carried by a rearwardly projecting shank 63 extending through the knob and provided with a manipulating head 64 which upon rearward pulling movement, causes the bridging element to bridge the spaced contact elements. The knob is preferably provided with an indicating device 65 which when disposed upwardly indicates the normal neutral position of the signal.

In use and operation, when the driver of the vehicle contemplates a stop he pulls rearwardly on the head 64 to bridge the spaced contacts 48 for closing the circuit to energize the lamp 41. This displays to following traffic the upraised open hand for giving an unmistakable "stop" signal. In event the operator contemplates making a right or a left turn, the knob 60 is rotated to the right or left, as the case may be, in which instances the cutout portions indicating a right or a left pointing hand, are brought into registry with the window openings 18 and 19, while, at the same time, the movable switch element 58 carried by the arm 57, is brought into engagement with either stationary contact 55 or 51, to automatically close the circuit and light the lamp 41 for unmistakably displaying the same to both approaching and following traffic.

I claim:

A signal including a casing having windows at opposite sides thereof, a strap supported within the casing with its longitudinal edges equi-distantly spaced from such sides, signal disks rotatable in the casing upon opposite sides of the strap, a rotatable toothed

element supported by the strap and having its ends fixed to the disks, the strap serving to retain the disks in spaced parallel relation, a channel-shaped member supported from the under face of the strap and extending longitudinally thereof, a rack bar slidable in the channel-shaped member and engaging the

rotatable element to rotate the disks, and a spring interposed between the rack bar and bottom wall of the channel-shaped member ¹⁰ and resiliently holding the rack bar against the rotatable element.

JUDSON B. FREIDAH.
